(57) **CLAIM**

The ornamental design for a multicomponent shock mitigation outsole, as shown and described.

DESCRIPTION

FIG. 1 is perspective view of a multicomponent shock mitigation outsole, showing my new design from the top, rear and right side;

FIG. 2 is a top plan view thereof;
FIG. 3 is a bottom plan view thereof;
FIG. 4 is a rear elevational view thereof;
FIG. 5 is a right side view thereof;
FIG. 6 is a left side view thereof; and
FIG. 7 is a perspective like FIG. 1, partially cut away to reveal surface contours.
FIG. 8 is another cut away perspective view, showing a spring cartridge, comprising a housing and a spring assembly, installed in the outsole;
FIG. 9 is a perspective view of the cartridge housing of the multicomponent shock mitigation outsole from the rear, right, and top in an open configuration;
FIG. 10 is a rear elevational view thereof;
FIG. 11 is a left side view thereof;
FIG. 12 is a right side view thereof;
FIG. 13 is a top plan view thereof;
FIG. 14 is a bottom plan view thereof;
FIG. 15 is a perspective view of the cartridge housing of the multicomponent shock mitigation outsole from the rear, right, and top in a closed configuration;
FIG. 16 is a rear elevational view thereof;

FIG. 17 is a left side view thereof;
FIG. 18 is a right side view thereof;
FIG. 19 is a top plan view thereof;
FIG. 20 is a bottom plan view thereof;
FIG. 21 is a perspective view of the spring assembly of the multicomponent shock mitigation outsole from the rear, right, and top in an open configuration;
FIG. 22 is a rear elevational view thereof;
FIG. 23 is a left side view thereof;
FIG. 24 is a right side view thereof;
FIG. 25 is a top plan view thereof;
FIG. 26 is a bottom plan view thereof;
FIG. 27 is a perspective view of the spring assembly of the multicomponent shock mitigation outsole from the rear, right, and top in a closed configuration;
FIG. 28 is a rear elevational view thereof;
FIG. 29 is a left side view thereof;
FIG. 30 is a right side view thereof;
FIG. 31 is a top plan view thereof; and,
FIG. 32 is a bottom plan view thereof.
